UNITED STATES PATENT OFFICE.

FLORENCE C. BIGGERT, JR., OF CRAFTON, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

TABLE-ACTUATING MECHANISM FOR ROLLING-MILLS.

1,161,441.

Specification of Letters Patent.

Patented Nov. 23, 1915.

Application filed March 27, 1915. Serial No. 17,363.

To all whom it may concern:

Be it known that I, FLORENCE C. BIGGERT, Jr., a citizen of the United States, residing at Crafton, Allegheny county, Pennsylvania, have invented a new and useful Improvement in Table-Actuating Mechanism for Rolling-Mills, of which the following is a full, clear, and exact description, reference being had to the accompanying drawings, forming part of this specification, in which—

Figure 1 is a side elevation, partly diagrammatic, of a rolling mill embodying my invention. Fig. 2 is a plan view of a portion of the mechanism. Figs. 3 and 4 are detail views hereinafter more fully described, and Fig. 5 is a wiring diagram illustrating one arrangement of the electric circuits.

20 My invention has relation to table mechanism for rolling mills; and more particularly for three-high mills of the type in which the bottom roll is vertically adjustable. In vertically adjustable mills of this 25 type, adjustable tables are employed; and it is desirable that means be provided for controlling the lowered position of the tables in accordance with the adjusted position of the bottom mill roll. My invention 30 is designed to provide simple and efficient means whereby the tables are automatically adjusted in their lowered positions in accordance with the position of said bottom roll.

35 In the accompanying drawings the numeral 2 designates the housing of a three-high mill, 3 the top roll, 4 the middle roll, and 5 the bottom roll. This bottom roll may be adjusted in any suitable or well 40 known manner. In the drawing (see Figs. 1 and 4) I have shown an adjusting screw 6 for this purpose operated by worm gearing 7 actuated from any suitable source of power, not shown.

45 8 designates a roll table at one side of the mill, and 9 a roll table at the opposite side. These roll tables may be in general of any usual or suitable form and hinged or pivoted as indicated at 10 to permit vertical movement thereof to suit the different 50 adjustments and passes of the rolls.

11 designates a table actuating electric motor connected by gearing 12 with a shaft 13 having mounted thereon a pinion 14

whose teeth engage the teeth of a longitudinally movable rack bar 15 (see Fig. 3). This rack bar has a link connection 16 at one end with a rocker arm 17 of a rock shaft 18.

19 is a table supporting and actuating member connected at its lower end to a second arm 20 fixed to the shaft 18 and at its upper end engaging the frame of the roll table 9. Preferably, this engagement is formed by the ball and socket members 21 and 22.

19 is a table supporting and actuating member connected at its lower end to a second arm 20 fixed to the shaft 18 and at its upper end engaging the frame of the roll table 9. Preferably, this engagement is formed by the ball and socket members 21 and 22.

For the purpose of actuating both tables simultaneously a link 23 connects the rocker arm 17 with a rocker arm 24 of a shaft 25 having a second rocker arm 26 connected by 70 a member 27, similar to the member 19, with the table 8.

It will be readily seen that when the motor 11 is operated in one direction or the other, the two tables will be simultaneously 75 raised or lowered.

For the purpose of automatically controlling the motor and enabling the tables to stop in the desired lowered positions, depending upon the particular adjustment of 80 the bottom mill roll 5, I provide mechanism controlled by said bottom roll, and which in turn controls the motor circuit. This arrangement is shown as being constructed and arranged as follows: The screw 6 has 90 its stem extended downwardly through the housing 28 for the worm gears 7, and engages one arm of a lever 29 which is connected by the link 30 and lever 31 with a vertically movable contact carrying member 90 32. This member 32 is arranged to slide vertically in the guides 33 and carries a relatively fixed contact 34 and a second contact 35 carried on one arm of a contact lever 36. 37 is a tappet arm on the frame of the 95 table 9 and which is adapted when the table is lowered to contact with the lever 36 and open the motor circuit which has been closed at the contacts 34 and 35. Inasmuch as the vertical position of these contacts is dependent upon the adjusted position of the bottom roll, through the connections described, it will be apparent that when the roll is adjusted to a relatively high position, the motor circuit will be opened and 100 the table stopped at a higher plane than when the roll 5 is at a lower position, with 105 a corresponding change in the position of

11 designates a table actuating electric motor connected by gearing 12 with a shaft 13 having mounted thereon a pinion 14

the contacts. In this manner, the tables will be automatically stopped in any case at the desired heights with reference to the adjustment of said roll 5.

5. The table 9 may be provided with a second tappet 38 adapted to engage a contact lever 39 when the tables are raised to their highest positions, and thus again open the motor circuit to automatically stop the tables in this position. As the adjustment of the middle roll never changes, this second set of contacts requires no adjustment, but may be supported on a fixed frame member 40.

15. By reference to Fig. 5 the arrangement of the motor circuits controlled by the contacts will be readily understood. When the reversing switch 41 is in the position shown in this figure, and the tables are in the elevated position shown in Fig. 1, the contacts 34 and 35 will be closed and the contact controlled by the contact lever 39 will be open. When said switch is thrown to the right the circuit of the motor is completed through the contacts 34 and 35, thereby starting the table in its downward movement. The contact carrier 39 will now close, but this will not affect the motor circuit, which at this time is open at the reversing switch 41, so far as this set of contacts is concerned. When the tappet arm 37 contacts with the contact carrier 36, the motor circuit is entirely opened and remains open until the reversing switch is thrown to its left hand position, at which time a complete circuit is established through the contact member 39 to raise the tables.

It will be readily understood that the particular construction and arrangement of the parts shown may be widely departed from without departing from the spirit and scope of my invention as defined in the appended claims. Thus, the connections controlled by the bottom roll for controlling the motor circuit may be widely varied; the actuating connections between the table operating motors and the tables may also be greatly changed, and various other changes can be made within the scope of the claims.

50. I claim:

1. In a three-high rolling mill having an adjustable bottom roll, the combination with a vertically movable table, of a motor for raising and lowering the table, and means for automatically varying the lowered position of the table in accordance with the adjusted position of the bottom mill roll, substantially as described.

2. A rolling mill having a vertically adjustable bottom roll, a vertically movable table, a motor for raising and lowering the table, and motor controlling devices controlled by the position of the bottom roll, substantially as described. 60

3. In a three-high mill having a vertically adjustable bottom roll, the combination of a vertically adjustable table, a motor and connections for raising and lowering the table, a circuit controlling device for said motor, and means for shifting the position of the 70 circuit controlling device by an adjusting movement of the bottom roll, substantially as described.

4. In a three-high mill having a vertically adjustable bottom roll, the combination of a 75 vertically movable table, a motor for raising and lowering the table, a movable circuit controlling device for said motor, means for automatically actuating said device to open the circuit when the table reaches a predetermined position, and actuating connections between said device and the bottom roll for shifting said device in accordance with different adjustments of said roll, substantially as described. 80

5. In a three-high mill having a vertically adjustable bottom roll, the combination of a vertically movable table, a motor for raising and lowering the table, a movable circuit controlling device for said motor, means for 90 automatically actuating said device to open the circuit when the table reaches a predetermined position, and actuating connections between said device and the bottom roll for shifting said device in accordance 95 with different adjustments of said roll, together with other circuit controlling connections for the motor and means for actuating the same when the table reaches its upper adjustment, substantially as described. 100

6. In a three-high rolling mill having a vertically adjustable bottom roll, the combination of vertically adjustable tables, motive means for simultaneously raising and lowering the two tables, a shiftable controlling device for the motive means, and connections for shifting the position of said device in accordance with the adjustment of the bottom roll, substantially as described. 105

In testimony whereof, I have hereunto set 110 my hand.

FLORENCE C. BIGGERT, JR.
